UNITED STATES PATENT OFFICE.

CHARLES H. SMITH, OF PAWTUCKET, AND ALFRED E. HAMPSON, OF LONSDALE, RHODE ISLAND.

UNIVERSAL WINDING MACHINE.

Application filed February 5, 1923. Serial No. 618,915.

To all whom it may concern:

Be it known that we, CHARLES H. SMITH and ALFRED E. HAMPSON, both citizens of the United States, residing, respectively, at 5 Pawtucket and Lonsdale, in the county of Providence and State of Rhode Island, have invented certain new and useful Improvements in Universal Winding Machines, of which the following is a specification.

10 Our invention relates to textile winding machines of the traverse bar type, and particularly to the means for controlling the strokes of the traverse bar and the traverse bar actuating member, which means is com- 15 monly known as the traverse bar lever stop.

It has heretofore been attempted to perform the controlling function by means of a plate having projections integral therewith in the path of the traverse bar actuating member, but this proved susceptible to breakage.

An object of the present invention is to successfully cushion the strokes of the traverse bar and the traverse bar actuating member without fracture or breakage; and another object is to quicken the initial impulse of the reverse motions of said member. Further objects and advantages of the invention will be apparent as it is better understood 30 from the following description.

Our invention consists, therefore, in the means for producing the results above referred to, substantially as hereinafter claimed.

35 In the accompanying drawings which are a part of this specification, and in which is shown merely a preferred form of embodiment of our invention,

Figure 1 is a plan, omitting the dust shields, and partially broken away, of the driving end of a textile universal winding machine embodying our invention,

Figure 2, a section on line 2—2 of Figure 1, looking in the direction of the arrows,

45 Figure 3, a section on the same line, looking in the direction opposite to the arrows,

Figure 4, a plan of the traverse bar lever stop,

Figure 5, a section of the same on line 50 5—5 of Figure 4, and

Figure 6, a fragmentary view of a traverse bar lever hub and adjacent saddle.

Like reference characters indicate like parts throughout the views.

55 The invention will be described in connec-

tion with the specific embodiment shown, and it will be understood that the invention is not to be limited by such specific showing except for such limitations as the claims im- 60 part.

In the drawings 10 is the frame and 11 the gainer case of a universal winding machine. Herein also 13 is the main shaft in the frame driven by pulleys 15, and carrying a gear 17 meshing with a gear 18 on a stud 19 and fast to which is a pinion gear 20, engaging a gear 21 on a stud 22. It also carries a pinion gear 23 meshing with a cam gear 24 on a stud 25. Fast to the gear 25 is a channel cam 26, engaged by a cam stud 28 70 on a crank arm 30 on rock shaft 32. To the latter are fixed saddles 34, and longitudinally movable thereon are the hubs 35 of traverse bar levers 36, one saddle and one hub only are herein shown. An end lug 37 75 on each hub, as shown in Figure 6, is normally held in a notch 38 in the adjacent saddle by a helical spring 39 engaging the hub with its inner end and abutting with its outer end a shoulder 41 on the rock shaft. 80 Integral with the hub 35 is a lateral finger or lug 42 having a curved face 43 and inclined lateral faces 44, as shown in Figure 2. A connecting rod 47 is pivotally attached at its ends to the lever 36 and to the traverse 85 bar 49 mounted in the frame, and reciprocated by the shaft 32 actuated by the described driving mechanism.

A pair of oppositely disposed laterally projecting spindles 51 with their intermeshing spindle gears 53 and 54 are also herein shown mounted in the frame; the gear 53 being driven through a gear 54' on shaft 13 in the usual manner.

Pivotedly mounted in the frame trans- 95 versely of the rock shaft 32 are clutch levers 55 each comprising a body or shank portion 56 having a central offset or bend 57 and a lateral cam arm 58. The latter is adapted to frictionally engage a clutch 60 on an ad- 100 jacent spindle 51 and to control the same. The shank is pivoted at one end by a stud 64 in the frame and has fixed to its other end a starting lever 66 journaled in the frame by which the clutch lever may be manually 105 tilted.

The offset 57 in each clutch lever 55 forms a recess 69 within which the finger 42 oscil- 110 lates, as shown in Figure 3. Bridging the recess is a plate 70 fastened by screws 72 to

the lever shank 56 at each end of the offset. As shown in Figures 4 and 5, the plate 70 has a marginal cavity 74 at each end of which there are upset from the material of 5 the plate ears 76 provided with perforations to receive a bar 77. In this case the bar or rod is in the form of a bolt comprising a shank 78 provided with a thread 79, a head 80, and a nut 81. The nut and bolt abut 10 tightly against the outer faces of the ears. Flat oblong fingers or plates 83 have elongated slots 84 near their upper ends through which loosely pass the member 77. The upper ends of these fingers are tightly pressed 15 against the ears 76 by a helical spring 86 surrounding the member 77 with its ends abutting against the inner faces of the fingers. In this case the spring terminates at its extremities in closely turned or double 20 coils 88. The fingers 83 depend below the plane of the plate 70 through the cavity 74 and recess 69 to positions at each side of the lug 42 so near the latter as to be in the path 25 of its movement in both directions. As each lug face 44 strikes its adjacent finger 83 the lower end of the latter slightly moves outwardly and its upper end tilts slightly inwardly, as permitted by the slots 84, storing up energy in the spring 86, which reacts 30 at the end of the stroke of the lug to initially accelerate its return, as well as serve as a cushion. The described construction is not subject to fracture or breakage through use.

We claim:—

35 1. In a universal winding machine, the

combination with the rock-shaft, and traverse bar lever, of a lug on the lever, a clutch lever provided with an offset adapted to receive the lug, ears supported on the clutch lever, a bar in the ears, and depending fingers on the rod at the side of the lug. 40

2. In a universal winding machine, the combination with the rock-shaft, the traverse bar lever fast thereto and means for actuating the shaft, of a lug on the lever, a clutch lever adjacent the shaft and disposed transversely thereto, ears supported on the clutch lever, a bar on the ears, and fingers yieldingly mounted on the rod in the path of the lug. 45

3. In a universal winding machine, a clutch lever, a plate on the lever, ears on the plate, a rod in the ears, depending fingers provided with openings near their ends adapted to loosely receive the rod, and a spring on the rod pressing the fingers against the ears. 50

4. In a universal winding machine, a clutch lever provided with an offset, a plate fast to the lever bridging the offset and provided with a cavity, ears on the plate at each end of the cavity, a rod in the ears, fingers on the rod abutting against the ears and depending through the cavity, and a helical spring on the rod engaging the fingers. 55 60

In testimony whereof we have affixed our signatures.

CHARLES H. SMITH.
ALFRED E. HAMPSON.
